UNITED STATES PATENT OFFICE

172,274

ORNAMENT FOR AN AUTOMOBILE HOOD

Marshall M. Fredericks, Birmingham, Mich., assignor to Chrysler Corporation, Highland Park, Mich., a corporation of Delaware

Application February 20, 1953, Serial No. 23,731

Term of patent 14 years

(Cl. D14—18)

To all whom it may concern:

Be it known that I, Marshall M. Fredericks, a citizen of the United States, residing in the city of Birmingham, county of Oakland, and State of Michigan, have invented a new, original, and ornamental Design for an Ornament for an Automobile Hood, of which the following is a specification, reference being had to the accompanying drawings, forming part thereof, in which:

Fig. 1 is a perspective view of an ornament for an automobile hood, showing my novel design;

Fig. 2 is a top plan view thereof on a larger scale;

Fig. 3 is a side elevation of the ornament; and

Figs. 4, 5, 6, 7, and 8 are sectional views taken on the lines 4—4, 5—5, 6—6, 7—7 and 8—8 respectively.

I claim:

The ornamental design for an ornament for an automobile hood, substantially as shown.
